UNITED STATES PATENT OFFICE.

LEO B. HART, OF VINTON, IOWA, ASSIGNOR OF ONE-HALF TO JOHN W. TOBIN, OF VINTON, IOWA.

WASHING AND DRYING MACHINE.

Application filed October 26, 1922. Serial No. 597,181.

To all whom it may concern:

Be it known that LEO B. HART, a citizen of the United States, residing at Vinton, in the county of Benton and State of Iowa, has invented certain new and useful Improvements in Washing and Drying Machines, of which the following is a specification.

My invention relates to a combined washing and drying machine.

An important object of the invention is to provide a machine of the above mentioned character, having means whereby the rotatable clothes holding element or drum may be held in a horizontal position, and turned, to wash or rinse the clothes, and then shifted to a vertical position, and rotated, to cause the clothes to be dried by the action of centrifugal force upon the wet clothes.

A further object of the invention is to provide a machine of the above mentioned character, which is convenient to adjust in its operation.

A further object of the invention is to provide a machine of the above mentioned character, which is strong, durable, and reliable in operation.

Other objects and advantages of the invention will be apparent during the course of the following description.

In the accompanying drawings forming a part of this specification, and in which like numerals are employed to designate like parts throughout the same,

Figure 1 is a central vertical longitudinal section through a machine embodying my invention, parts being in elevation,

Figure 1^a is a side elevation of a bearing plate and associated elements, parts in section,

Figure 2 is an end elevation of the same,

Figure 3 is a perspective view of the head or end of the drum,

Figure 4 is a horizontal section taken on line 4—4 of Figure 1,

Figure 5 is a side elevation of the machine,

Figure 6 is a perspective view of the drum yoke,

Figure 7 is a plan view of the driving shafts, associated elements being in section,

Figure 8 is a detail section through the bearing sleeve and associated elements, parts broken away,

Figure 9 is a perspective view of the supporting yoke for the bearing sleeve,

Figure 10 is a similar view of a latch device for the lever.

In the drawings, wherein for the purpose of illustration is shown a preferred embodiment of my invention, the numeral 15 designates corner posts preferably formed of angle iron, and projecting downwardly in the form of legs 16. These corner posts are connected by transverse bars 17 and 18, and also by longitudinal bars 19. These posts and the bars constitute a supporting frame for the machine.

Suitably mounted within the supporting frame is a casing 20, which may be formed of sheet metal or the like, while any other suitable material may be employed. The upper portion of this casing constitutes a drying chamber 21 while its lower portion is in the form of a water holding chamber 22, serving as an ordinary tub. The chamber 21 projects longitudinally beyond the chamber 22, at one end, providing an overhanging bottom wall 23 and a diagonal wall 24, as shown. This arrangement affords an exterior space 25 for the reception of the motor and other operating elements, to be described. The top of the chamber 21 may be closed by means of a cover 26, which is hinged to the frame at 27, and may be held in the closed position by a latch 28, or other suitable means. There is a space 29 within the frame, exteriorly of the casing 20, and this space is adapted for the reception of driving means, to be described. This space may be closed by a door 30, hinged to the frame at 31, Figure 4, and held closed by a latch 32, or the like.

The numeral 33 designates a sleeve bearing, which is mounted to swing in a vertical plane, longitudinally of the machine, and to assume horizontal and vertical positions. This sleeve bearing extends through and is rigidly clamped within a collar 34, integral with the diverging arms 35 of a substantially V-shaped supporting yoke 36. The arms 35 are provided at their ends with horizontal extensions 37, which are pivotally mounted in bearings 38, rigidly secured to the casing 20, by any suitable means. One of the horizontal extensions 37 is rigidly connected with a lever 39, operating in proximity to the side of the casing 20 and

adjacent a latch bar 40, having resilient latches 41 and 42 stamped therefrom, and projecting outwardly. As shown in Figure 5, when the lever 39 is swung to the extreme horizontal or vertical position, it will lie behind the resilient latch element, and hence will be locked in this position, until the latch element is depressed, to permit of the movement of the lever. By this means the support yoke 36 may assume horizontal and vertical positions, carrying the sleeve bearing 33 with it, as is obvious. It is thus seen that the sleeve bearing 33 is supported by this yoke, and the strains placed upon the sleeve bearing are in turn transmitted to the support yoke 36.

The sleeve bearing 33 projects into the interior of the casing 20, and passes through the diagonal wall 24, and it is desired to effect a water tight connection between this sleeve bearing and the diagonal wall. To accomplish this, the sleeve bearing 33 is provided with a ball 43 formed integral therewith, and this ball is pivotally mounted with a plate 44, having a spherically curved face to contact with the ball. The plate 44 is secured to the wall by bolts or rivets 46 or the like. The ball 43 is equipped with trunnions 47 pivoted within sockets 48, formed on the plate 44. The numeral 49 designates a ring of packings, preferably arranged upon the outer side of the plate 44, and contacting with the ball 43 to effect a water tight joint. It is obvious that the detailed construction of the joint may be varied, as may be found advantageous.

The numeral 50 designates a spindle, rotatable within the bearing sleeve 33, and engaging bearing balls 51, held in place by caps 52 or the like. This spindle 50 is provided with a ring 53, rigidly mounted thereon, to engage with the bearing balls 51, thus constituting an end thrust bearing, which is particularly needed when the spindle is operating in a vertical position. The spindle is therefore free to rotate within the bearing sleeve 33, but cannot partake of restricted longitudinal movements therein.

Preferably formed integral with the inner end of the bearing sleeve 33, Figures 1 and 6, is an approximately U-shaped drum yoke 54, embodying arms 55. These arms are adapted to extend upon opposite sides of a drum 56, as clearly shown in Figure 4. The arms 55 are provided at their ends with headed studs 57, for insertion within transverse notches 58, formed in the ends of a resilient latch bar 59, pivoted to a head or end 60 of the drum. The latch bar 59 is pivoted upon a trunnion 59', rigidly secured to the head 60, and this trunnion is adapted to enter a U-shaped bearing 60', secured to the side of the casing 20. This head is provided with a flange 61, to enter

the open end of the drum, and the latch bar 59 is thus connected with the yoke 54, to hold the head upon the drum in the closed position. By virtue of the flange 61 of the head 60, and associated elements, it is apparent that the yoke 54 constitutes a connecting means between the outer end of the drum and the bearing sleeve 33.

The opposite end 62 of the drum 56 has a base or plate 63 rigidly secured thereto, and this plate is equipped with a socket 64, having an opening 65, which is square in cross section, to receive the end 66 of the spindle 50, which end is also square in cross section. It will be further seen that the yoke 54 and associated elements serve to retain the socket 64 upon the end 66.

The drum 56 is preferably of the shape shown, having a cylindrical intermediate portion 67, and diagonal portions 68. The periphery of the drum is preferably apertured, as shown at 69. As clearly illustrated in Figure 1, when the drum is in the horizontal position, it operates within the water in the lower chamber 22, but when the drum is shifted to the vertical position, as indicated in dotted lines in Figure 1, the drum is in the upper chamber 21.

Rigidly mounted upon the outer end of the spindle 50 is a combination gear 70, having a cylindrical gear portion 71, and a beveled gear portion 72.

The combination gear 70 is of course an integral casting, and its cylindrical gear portion 71 is adapted for engagement with the segmental gear or gear element 73, Figures 1 and 2, when the spindle 50 is shifted to the horizontal position. The segmental gear 73 is pivotally mounted upon the stud 74, carried by the transverse bar 17. The segmental gear 73 is adapted to be oscillated, by means to be described, and the diameter of the segmental gear 73 being much larger than the diameter of the cylindrical gear portion 71, the spindle 50 will be given a plurality of rotations in one direction, and then a plurality of rotations in the opposite direction, alternately. The segmental gear 73 has a pin 75 secured thereto, near its periphery, and this pin has pivotal connection with a pitman 76, extending downwardly and arranged upon the inner side of a large driving gear 77. The pitman 76 is pivotally connected with the gear 77 by means of a pin 78. The distance between the pin 78 and the pivotal support 79 of the gear 77 is much less than the distance between the pin 75 and the pin 74, and hence as the gear 77 is driven continuously in the same direction, the pitman 76 will effect an oscillatory movement of the gear 73.

Referring now more particularly to Figures 1 and 7, the numerals 81 and 82 designate power shafts, disposed in end to end relation, but free from connection with each

other. The shaft 81 is journaled within bearings 83 and 84, while the shaft 82 is journaled in a bearing 85. These power shafts are free to rotate, but cannot partake of perceptible longitudinal movement. The power shaft 82 is equipped with a pinion 86 in permanent engagement with the gear 77.

The power shaft 81 has a vertical beveled gear 87 rigidly mounted thereon, and adapted to be engaged by the beveled gear portion 72, when the combination gear is swung to the vertical position, as indicated in Figure 1.

The numeral 88 designates a motor, mounted upon a platform 89, in turn attached to the frame work of the machine, and located in the space 25. This motor drives a pulley 90, engaging and driving a belt 91, extending downwardly to engage a pulley 92, which is free to turn upon the adjacent ends of the power shafts 81 and 82, but cannot partake of perceptible longitudinal movement thereon. This pulley is provided with oppositely arranged clutch faces 93 and 94, adapted to have frictional engagement with clutch heads 95 and 96 respectively. These clutch heads are keyed upon the shafts 81 and 82 respectively, so that they may move longitudinally thereon, and turn therewith. The clutch heads 95 and 96 are urged toward each other by springs 97 and 98, as shown. The clutch heads 95 and 96 are engaged by a shifting fork 99 carried by a lever 100, pivoted at 101. The springs 97 and 98 tend to return the clutch heads to the neutral position, so that both clutch heads may slide with the clutch faces of the pulley 92. When the lever 100 is swung from this neutral position in either direction, one clutch head will have frictional engagement with the clutch face of the pulley, while the other clutch head will disengage the corresponding clutch face. It is thus seen that means are provided whereby the pulley 92 may be employed to alternately drive either power shaft 81 or 82, or the pulley 92 will run idle without rotating these power shafts.

The operation of the machine is as follows:

With the spindle 50 in the vertical position, as indicated in dotted lines, in Figure 1, the head or cover 60 of the drum may be removed and the clothes or the like to be washed introduced into the drum. The head is now locked to the drum by engaging the latch bar 59 with the headed studs 57. The lever 39 is now shifted to the horizontal position, Figure 5, and the drum 56 will assume a horizontal position, with its lower portion operating in the water. With the lever 39 locked in this horizontal position, the lever 100 is swung in the direction to cause the clutch head 96 to frictionally en-

gage the clutch face 94. The motor 88 will therefore drive the gear 86, which in turn will drive the gear 77, effecting an oscillatory movement of the segmental gear 73. This segmental gear engaging the cylindrical portion 71 of the combination gear 70, will rotate the drum 56 for a plurality of rotations, alternately, in opposite directions. The power shaft 81 is now idle. After the washing operation is completed and it is desired to dry the clothes, the lever 100 is returned to the neutral position. The lever 39 is now swung to the vertical position, whereby the spindle 50 and the drum assume the vertical position shown in dotted lines in Figure 1. The beveled portion 72 of the combination gear 70 now engages the beveled gear 87, which is adapted to drive the spindle and the drum at an increased speed. The lever 100 is now shifted to bring the clutch head 95 into engagement with the clutch face 93, and the motor will therefore drive the power shaft 81. The drum rotating at a high speed, subjects the wet clothes to the action of centrifugal force whereby they are dried in a manner well known in the art.

After the drying operation, the rotation of the drum is stopped, and the clothes may be removed, as is obvious.

It is to be understood that the form of my invention herewith shown and described is to be taken as a preferred example of the same; and that various changes in the shape, size, and arrangement of parts may be resorted to without departing from the spirit of my invention or the scope of the subjoined claims.

Having thus described my invention, what I claim is:

1. In a washing machine of the character described, a receptacle for holding water, a pivotally supported sleeve-bearing adapted to be shifted to substantially horizontal and vertical positions, a pivotally supported support yoke arranged near the receptacle and engaging the sleeve-bearing at a point remote from its pivot, a spindle rotatable within the sleeve bearing, a drum carried by one end of the spindle, gear means carried by the spindle, and spaced driving gear elements adapted to be alternately engaged by said gear means.

2. In a washing machine of the character described, a receptacle, a bearing pivotally supported near the receptacle and adapted to swing in a substantially vertical plane, a spindle rotatable within the bearing, a drum for operation within the receptacle and having its rear end secured to the spindle, a drum yoke carried by the bearing and extending to the forward end of the drum, means for connecting the forward end of the drum with the drum yoke, gear means mounted upon the spindle, and a pair of

spaced gear elements adapted to be alternately engaged by said gear means.

3. In a washing machine of the character described, a receptacle, a bearing pivotally supported near the receptacle and adapted to swing in a substantially vertical plane, a spindle rotatable within the bearing, a drum for operation within the receptacle, a socket secured to the rear end of the drum and adapted to be detachably mounted upon the forward end of the spindle, a drum yoke carried by the bearing and extending to the forward end of the drum, means for detachably connecting the forward end of the

10 drum with the drum yoke, gear means secured to the rear end of the spindle, and a pair of spaced gear elements adapted to be alternately engaged by said gear means.

4. In a washing machine of the character described, a receptacle having a lower chamber to receive water, a pivotally supported support yoke arranged near the receptacle, a sleeve bearing extending through the wall of the receptacle and rigidly connected with the support yoke, means for swinging the support yoke upon its pivot, a spindle within the sleeve bearing, a drum carried by one end of the spindle, a gear carried by the spindle, and spaced driving gear elements adapted to be alternately engaged by said gear.

5. In a washing machine of the character described, a receptacle adapted to receive water, a pivotally supported support yoke arranged near the receptacle, a lever connected with one end of the support yoke to turn it upon its pivot, a sleeve bearing secured to the support yoke and extending through the wall of the receptacle, means for effecting a substantially water tight joint between the sleeve bearing and the wall of said receptacle, a spindle within the sleeve bearing, a drum carried by one end of the spindle, a gear carried by the opposite end of the spindle, a pair of spaced driving gear elements to alternately engage said gear, and means to drive said gear elements.

6. In a washing machine of the character described, a receptacle, a spindle, a sleeve bearing rotatably receiving the spindle, a drum mounted within the receptacle and carried by one end of the spindle, means for pivotally supporting the sleeve bearing so that it may swing substantially vertically, a drum yoke carried by the inner end of the sleeve bearing and surrounding the drum, a head for the drum, a latch bar carried by the head and provided at its ends with transverse notches, headed studs carried by the drum yoke for insertion within said notches, a gear carried by the opposite end of the spindle, and a pair of spaced gear elements adapted to be alternately engaged by said gear.

7. In a washing machine of the charac-

ter described, a receptacle, a vertically swinging bearing arranged near the receptacle, a spindle rotatable within the bearing, a drum having its rear end mounted upon the forward end of the spindle, a drum yoke carried by the bearing and extending to the forward end of the drum, a head having interlocking engagement with the forward end of the drum, a bar carried by the head and engaging the ends of the drum yoke, gear means carried by the rear end of the spindle, and a pair of spaced gear elements adapted to be alternately engaged by said gear means.

8. In a washing machine of the character described, a receptacle, a vertically swinging bearing arranged near the receptacle, a spindle rotatable within the bearing, a drum having its rear end mounted upon the forward end of the spindle, a drum yoke carried by the bearing and extending to the forward end of the drum, a head engaging the forward end of the drum, a bar carried by the head and engaging the ends of the drum yoke, a trunnion carried by the head, a bearing arranged to receive the trunnion when the drum is swung to the substantially horizontal position, gear means secured to the rear portion of the spindle, and a pair of spaced gear elements adapted to be alternately engaged by said gear means.

9. In a washing machine of the character described, a receptacle, a vertically swinging bearing arranged near the receptacle, a spindle rotatable within the bearing, a drum mounted upon the forward end of the spindle, a drum yoke carried by the bearing and extending to the forward end of the drum, a head engaging the forward end of the drum, a trunnion carried by the head, a latch bar pivoted upon the trunnion and having oppositely faced notches near its ends, headed elements carried by the ends of the drum yoke for receiving the notched ends of the latch bar, a stationary bearing arranged for receiving the trunnion when the drum is swung to the substantially horizontal position, gear means secured to the rear portion of the spindle, a pair of spaced gear elements adapted to alternately engage said gear means, and means to swing the drum to the horizontal and vertical positions and to hold the same in these selected positions.

10. In a machine of the character described, a pivotally mounted support adapted to swing substantially vertically, a spindle rotatable within the support, means for shifting the support to the raised and lowered positions, a drum carried by the spindle, a cylindrical gear and a beveled gear secured to said spindle, a driving beveled gear arranged in the path of travel of said beveled gear for engagement therewith, a second gear spaced from the beveled gear

and arranged in the path of travel of said cylindrical gear, and means for driving the beveled gear and the second gear.

11. In a machine of the character described, a pivotally mounted support adapted to swing substantially vertically, a spindle rotatable within the support, means for shifting the support to the raised and lowered positions, a drum carried by the spindle, gear means secured to one end portion of the spindle, a driving element dis-

posed permanently in the path of travel of said gear means for engagement therewith when the drum is shifted to the substantially horizontal position, a second driving element disposed permanently in the path of travel of said gear means to engage therewith when the drum is shifted to the substantially vertical position, and means to rotate said driving elements.

In testimony whereof I affix my signature.
LEO B. HART.
